[57] CLAIM

The ornamental design for an inverted bottle holder, as shown and described.

DESCRIPTION

FIG. 1 is a perspective view of an inverted bottle holder showing my new design;

FIG. 2 is a right side elevational view thereof, the left side elevational view being a mirror image thereof;

FIG. 3 is a top plan view thereof;

FIG. 4 is a bottom plan view thereof;

FIG. 5 is a rear elevational view thereof; and,

FIG. 6 is a cross-sectional view thereof, taken along line 6—6 in FIG. 3.

FIG. 1

FIG. 2

FIG. 3

FIG. 4

FIG. 5

FIG. 6
